UNITED STATES PATENT OFFICE.

WILLIAM HANCOCK WEDDINGTON, OF DURANGO, COLORADO, ASSIGNOR
TO HIMSELF AND WILLIAM BAYLY, OF SAME PLACE.

SASH-FASTENER.

SPECIFICATION forming part of Letters Patent No. 369,670, dated September 6, 1887.

Application filed January 29, 1887. Serial No. 225,903. (No model.)

To all whom it may concern:

Be it known that I, WILLIAM HANCOCK WEDDINGTON, a citizen of the United States, residing at Durango, in the county of La Plata 5 and State of Colorado, have invented certain new and useful Improvements in Sash Locks and Lifts; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 My invention relates to that class of devices known as "sash locks and lifts," and has for its object the production of a reversible lock and lift of novel construction, simple, automatically locking, and easily applied, and that 20 may be cheaply manufactured.

25 In the drawings, Figure 1 is a front elevation (partly in section) of a portion of a window sash and frame, showing my improvement attached thereto. Fig. 2 is a view of the locking-bolt. Fig. 3 is a side view (partly 30 in section) of the complete device. Figs. 4, 5, and 6 are detail views of the lock-sheath and the lift.

35 A is a metal sheath or tube, its inner face, *a*, being at right angles to the body of the tube, its opposite or outer end, *B*, having an oblique face, *b*, provided at its upper portion with a parallel oblique-faced stop, *c*, forming two shoulders, *d d'*. (Clearly shown in Fig. 5.) The top and bottom of sheath *A* are provided with longitudinal splines *d''*.

40 C is the locking-bolt, having a reduced stem, *D*, adapted to receive a spiral spring, *E*. *e* and *f* are shoulders on bolt *C* and inside of sheath *A*, respectively, forming two opposing abutments for spiral spring *E*. Near its outer end stem *D* is recessed, as at *g*, to receive the end of binding-screw *h*.

45 *F* is the lift. (Shown in perspective in Fig. 4 and in front elevation in Fig. 6.) It consists of a head, *G*, centrally perforated at *i*, so as to fit easily on stem *D*. A screw-threaded hole, *j*, is made in its front face to receive binding-screw *h*. The right and left sides of head *G* 50 are cut in two parallel oblique planes, *H' I'* and *H I*, each plane ending on the same cen-

tral plane and connected to each other by shoulders *k' l'* and *k l*. One oblique surface may be used on the head of lifter *F*, but I prefer two such surfaces, as herein shown. By 55 constructing the right and left hand sides of head *G* each in two parallel planes, instead of in one plane, I reduce the friction of the opposing oblique surfaces, and am also enabled thereby to obtain the shoulders or stops *k' l'* 60 and *k l*, so as to give a certain and positive check to the compression of spring *E*. The same is true, also, of the oblique face *b* of sheath *A* and its parallel oblique stop *c*. The tail or hand piece *F* of the lift is roughened, as at *m*, 65 so as to prevent slipping from the hand. The outer or exposed end of the device is covered by a guard, *K*.

To apply my device to either the upper or the lower sash of a window, I first bore a hole 70 through the sash, as at *L*, Fig. 1, and insert sheath *A* therein from the outside of the sash and flush with the same. The splines *d''* will prevent any rotary motion of the sheath when in place. I now insert bolt *C*, with its spiral 75 spring *E*, in place, then temporarily replace the window-sash in the frame. This will hold the bolt pressed inwardly. Now head *G* of the lift is slipped over stem *D*, and cap or guard *K* is pushed in place over head *G* of the lift, 80 (recess *g* of stem *D*, screw-hole *j* of lift, and screw-hole in cap *K* being in alignment.) The binding-screw *h* is now inserted and screwed home. Recesses *M* for bolt *C* are bored in the window-frame at any desired distances apart. 85

The operation of my device is as follows: To unlock the sash I pull the part *F* of the lift outwardly and upward until the shoulder *l'* or *l* engages with shoulder *d'* or *d* of sheath *A*. This motion withdraws bolt *C* from recess *M* in the window-frame. The sash may now be raised by means of the lift to any desired point and locked there by permitting the lift to resume its downward or normal position when locked, as shown in the lower part 95 of Fig. 1.

This device may be applied to either the right or left hand side of a window, and may be manufactured and sold with the parts all assembled, ready for use.

100 What I claim as new, and desire to secure by Letters Patent, is—

The sash lock and lift consisting of sheath A, locking bolt C, and spiral spring E, sheath A having at its outer beveled end a projecting nib or stop, e, in combination with a lift, F², 5 having two oblique surfaces provided with stops or shoulders k' l' and k l, whereby the sash may be unlocked and raised, as herein set forth.

In testimony whereof I affix my signature in presence of two witnesses.

WILLIAM HANCOCK WEDDINGTON.

Witnesses:

FERGUS RICHARD GRAHAM,
GEO. MARSH.
